US0D1083766S

(12) **United States Design Patent** (10) **Patent No.:** **US D1,083,766 S**
(45) **Date of Patent:** **** Jul. 15, 2025**

(54) **SIGNAL TERMINAL**

(71) Applicant: **Luxshare Precision Industry Company Limited**, Shenzhen (CN)

(72) Inventors: **Liang Yu**, Shenzhen (CN); **Min Fan**, Shenzhen (CN)

(73) Assignee: **LUXSHARE PRECISION INDUSTRY COMPANY LIMITED**, Shenzhen (CN)

(**) Term: **15 Years**

(21) Appl. No.: **29/881,141**

(22) Filed: **Dec. 28, 2022**

(30) **Foreign Application Priority Data**

Aug. 29, 2022 (CN) 202230567977.7
